KNOB FOR DOORS, DRAWERS, AND THE LIKE

Don Heyer, Fullerton, Calif., assignor to Hyer Hardware
Mfg., Co., Anaheim, Calif., a corporation of California

Filed Sept. 10, 1963, Ser. No. 76,534

Term of patent 14 years

(CL D10—8)

The figure is a perspective view of a knob for doors, drawers, and the like showing my new design.

The dominant features of the design reside in the portions shown in full lines.

I claim:

The ornamental design for a knob for doors, drawers, and the like, as shown and described.
